UNITED STATES PATENT OFFICE

109,124

DESIGN FOR A WALL PLAQUE

Alfred Dino Buralli, Chicago, Ill., assignor to Marbello Artercraft Co., Inc., Chicago, Ill., a corporation of Illinois

Application October 11, 1937, Serial No. 72,120

Term of patent 3½ years

To all whom it may concern:

Be it known that I, Alfred Dino Buralli, a citizen of the United States, residing at Chicago, in the county of Cook and State of Illinois, have invented a new, original, and ornamental Design for a Wall Plaque, of which the following is a specification, reference being had to the accompanying drawing form part thereof.

Fig. 1 is a front elevational view of a wall plaque showing my new design; and

Fig. 2 is a top view thereof.

I claim:

The ornamental design for a wall plaque substantially as shown.

ALFRED DINO BURALLI.
